US0D1051387S

(12) **United States Design Patent** (10) **Patent No.:** **US D1,051,387 S**
(45) **Date of Patent:** **** Nov. 12, 2024**

(54) **SCANNER WITH A TIP**

(71) Applicant: **3 Shape A/S**, Copenhagen (DK)

(72) Inventors: **Mikael Nielsen**, Copenhagen (DK); **Nicolas Boda**, Copenhagen (DK); **Anders Larsen**, Copenhagen (DK); **Alexander Bruun Christiansen**, Copenhagen (DK); **Mads Grønlund Andersen**, Copenhagen (DK); **Oleksii Borodianskyi**, Copenhagen (DK); **Finn Hansen**, Copenhagen (DK); **Oliver Sundberg**, Copenhagen (DK); **Dmytro Chupryna**, Copenhagen (DK)

(73) Assignee: **3SHAPE A/S**, Copenhagen K (DK)

(**) Term: **15 Years**

(21) Appl. No.: **29/862,314**

(22) Filed: **Dec. 8, 2022**

(51) LOC (14) Cl. **24-02**

(52) U.S. Cl.

USPC **D24/152**

(74) *Attorney, Agent, or Firm* — Polson Intellectual Property Law P.C.; Margaret Polson

(57) **CLAIM**

The ornamental design for a scanner with a tip as shown and described.

DESCRIPTION

FIG. 1 is a top side isometric view of our new design for a scanner with a tip.

FIG. 2 is a bottom side isometric view of FIG. 1.

FIG. 3 is a top plan view of FIG. 1.

FIG. 4 is a bottom plan view of FIG. 1.

FIG. 5 is a left side elevation view of FIG. 1.

FIG. 6 is a right side elevation view of FIG. 1.

FIG. 7 is a front side elevation view of FIG. 1; and,

FIG. 8 is a back side elevation view of FIG. 1.

The features shown in broken lines and light grey in the drawing depict environmental subject matter only and form no part of the claimed design. The dash dot dash lines represent unclaimed borders.

1 Claim, 7 Drawing Sheets
